UNITED STATES PATENT OFFICE

151,941

DESIGN FOR A SLIP

Leo Rose, Lawrence Myers, and Moses Richter,
Mount Gilead, N. C., assignors to United Mills
Corporation, a corporation of North Carolina

Application September 23, 1947, Serial No. 141,544

Term of patent 14 years

(Cl. D3—26)

To all whom it may concern:

Be it known that we, Leo Rose, Lawrence Myers, and Moses Richter, citizens of the United States, residing at Mount Gilead, in the county of Montgomery and State of North Carolina, have invented a new, original, and ornamental Design for a Slip, of which the following is a specification, reference being had to the accompanying drawing, forming part thereof.

In the drawings:

Figure 1 is a perspective view of a slip embodying our new design, viewed from the front;

Figure 2 is a rear elevation;

Figure 3 is a side elevation.

We claim:

The ornamental design for a slip, as shown.

LEO ROSE.

LAWRENCE MYERS.

MOSES RICHTER.
